Primary Examiner — Ian Simmons*Assistant Examiner* — Dana L Meyrow(74) *Attorney, Agent, or Firm* — Leanne Taveggia Farrell; Westman, Champlin & Koehler, P.A.(57) **CLAIM**

We claim the ornamental design for a bottle, as shown and described.

DESCRIPTION

FIG. 1 is a top perspective view of a bottle showing our new design;

FIG. 2 is a side elevation view thereof, the opposing side, front and rear elevations being identical;

FIG. 3 is a top plan view thereof; and,

FIG. 4 is a bottom plan view thereof.

The broken lines are included for purposes of illustration and form no part of the claimed design.
